UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A CASINO.

SPECIFICATION forming part of Design No. 19,550, dated December 31, 1889.

Application filed December 7, 1889. Serial No. 332,974. Term of patent 3½ years.

To all whom it may concern:

Be it known that I, WILLIAM K. BENEDICT, of the city and county of New York, in the State of New York, have invented and produced a new and original Design for the Exterior of a Casino, of which the following is a specification, reference being had to the accompanying drawings, forming a part thereof.

Figure 1 is a perspective view of a casino embodying my design. Fig. 2 is a ground or plan view of the first story. Fig. 3 is a similar view of the second story.

Similar letters of reference designate corresponding parts in all the figures.

15 A casino embodying my design comprises a first and second story and an attic story, the whole being surmounted by a gable roof.

The first and second stories are substantially flat upon their exteriors. Extending 20 from the first story is a porch A, which porch is surmounted at the front of the casino and

at the second story by a balcony B. The porch and balcony A B are arranged at one corner of the casino. The gable roof slopes to the front and rear sides and terminates at 25 about the top of the second story. Upon the front slope is a dormer-window C, provided with a hipped roof terminating at its rear in a gable roof c. At one side of the dormer window C and rising from the front slope of 30 the roof is an octagonal-shaped balcony D, surmounted by an ogee-shaped roof E, of octagonal form, which roof is represented as being supported by pillars e.

What I claim is—

35 The design for the exterior of a casino, substantially as herein shown and described.

WILLIAM K. BENEDICT.
